United States Patent Office

Des. 232,751

Patented Sept. 10, 1974

232,751

TRUNDLE TOY

Eugene J. Echterling, Woodland Hills, Calif., assignor to
Questor Corporation, Toledo, Ohio

Filed Jan. 24, 1973, Ser. No. 326,304

Term of patent 14 years

Int. Cl. D21—01

U.S. Cl. D34—15 D

Fig. 2.

Fig. 3.

FIG. 1 is a perspective view of a trundle toy showing my new design;

FIG. 2 is a front elevational view thereof; and

FIG. 3 is a side elevational view.

For ease of illustration, portions of the handle have been omitted in FIGS. 2 and 3.

I claim:

The ornamental design for a trundle toy, as shown and described.
